UNITED STATES PATENT OFFICE.

JAMES CUSTIS RUFFCORN, OF POLK, OHIO.

FENCE.

SPECIFICATION forming part of Letters Patent No. 364,187, dated May 31, 1887.

Application filed March 11, 1887. Serial No. 230,514. (No model.)

To all whom it may concern:

Be it known that I, JAMES CUSTIS RUFFCORN, a citizen of the United States, residing at Polk, in the county of Ashland and State 5 of Ohio, have invented a new and useful Improvement in Fence-Supports, of which the following is a specification.

My invention relates to improvements in fence posts or supports, and is applicable to 10 all styles and constructions of fences, its objects being to economize space and material in building the fence, to prevent the fence from sagging or being blown down, to build, remove, or repair the fence with rapidity and 15 ease, and to provide a fence that will be both durable and of simple construction. I accomplish these objects by the construction and arrangement of the rail-supports or posts, and of the means of connection of the rails thereto, 20 as hereinafter described, illustrated in the drawings, and pointed out in the appended claims.

In the accompanying drawings, Figure 1 is a perspective view of a fence with my invention 25 forming part thereof. Fig. 2 is a perspective view of one of the supports detached. Fig. 3 is a perspective view of the binding-wire which connects the supports and rails detached from the fence. Fig. 4 is a modified form of 30 looping said wire. Fig. 5 is an end view of the completed fence.

Referring to the drawings by letter, A A 35 designate the rails of the fence, the ends of those of one section being introduced a suitable distance between the ends of those of adjoining sections.

B are the fence supports or posts, each made 40 of two similar sections on opposite sides of the fence, and each section composed of a vertical post, C, having its lower end, c, pointed and provided with a circumferential shoulder, c', adjacent to the pointed part, and a brace or truss-beam, D, standing outward at a suitable supporting angle from the post, with its lower 45 end in the same horizontal plane as the shoulder c', and thereby stayed by the ground when the pointed end of the post is driven therein, and the shoulder c' rests upon the surface thereof.

50 The posts C rest against the opposite sides of

the fence at the joints of the sections, and the rails of adjoining sections project suitable distances on each side thereof.

E is the wire that binds the supports to the rails at said points. The said wire is bent below the lowest rail of a section, and passes up thence, as at e e, on each side, and over the oppositely-inclined brace-beams D, near the tops of the same, and thence around the posts C, on the inner side thereof, as at e' e', and with one of the ends e' passing completely around the two posts C C. The ends of the wire are then secured together by twisting, or otherwise, so as to make it bind firmly on all the rails, posts, and brace-beams. Both inside strands, e', of 65 wire pass between rails of adjacent sections.

Fig. 4 shows a different arrangement of the wire. In this modification the wire passes around each post C, and attached brace-beam D, separately, and is looped entirely around 70 the lowest rail in the section, on each side of the support.

The wire may be arranged in any manner around the supports and rails that will support the latter upon the former and will draw 75 the two sections of the supports together.

It is evident that the improvement may be applied to any fence, for in a picket-fence the wire may pass under the lowest longitudinal binding-rail of the same, and in a board fence, 80 if the boards are very thin, they may have suitable blocks secured to their ends. The wires in binding on the parts draw the posts C C together, so that they bear upon the rails and prevent longitudinal motion or slipping 85 thereof, and also tend to prevent the rails from sagging.

The fence is prevented from blowing down by the brace-beams D.

The fence is straight, so as to require less 90 timber than a worm-fence, and requires no nails in its construction, so that it is evidently cheap and simple of construction, and can be easily taken down, put up, or repaired.

In building the fence, one row of sections 95 the supports are first driven into the earth at proper distances apart, the rails carried to the proper points, and the sections of supports for the other side put in place and secured with the wires, as described.

Having described my invention, I claim—

1. The combination of the supports, each composed of two sections consisting of a vertical post, C, provided with a pointed lower end, 5 e, and a circumferential shoulder, e', and a brace-bar, D, standing outward from said post at a suitable angle, the rails, the ends of those in each fence-section being inserted between the ends of those in each adjacent section, and 10 the wires passing under the lowest rail in each section and around the posts and brace-bars, so as to uphold the rails and bind them between the posts C, substantially as specified.
2. The combination of the supports, each 15 consisting of two similar opposite sections, composed of the vertical post C and brace bar

or beam D, the rails which in each section have their ends inserted between the ends of those in adjacent sections, and the wires E, running below the lowest rail in each section, 20 then passing upward at e e on each side, passing over the upper ends of the brace-beams D, forming two strands, e' e', on one side of the posts C C and only one strand, e², on the other side of said posts, substantially as specified. 25

In testimony that I claim the foregoing as my own I have hereto affixed my signature in presence of two witnesses.

JAMES CUSTIS RUFFCORN.
